UNITED STATES PATENT OFFICE.

HENRY BOGGIS, OF PHILADELPHIA, PENNSYLVANIA.

DESIGN FOR A GAME-BOARD.

SPECIFICATION forming part of Design No. 33,151, dated September 4, 1900.

Application filed July 23, 1900. Serial No. 24,608. Term of patent 14 years.

To all whom it may concern:

Be it known that I, HENRY BOGGIS, a citizen of the United States, residing at Philadelphia, in the county of Philadelphia and State of Pennsylvania, have invented and produced a new and original Design for Game-Boards, of which the following is a specification, reference being had to the accompanying drawing, forming part thereof.

10 The accompanying drawing represents a plan view of the game-board, illustrating my new invention.

As illustrated in the drawing, the leading or material feature of the design consists in 15 a quadrilateral figure A, equilateral and equiangular, inclosing eighty-one smaller but similarly-shaped quadrilateral figures B, arranged as shown in the drawing. Inclosed also within the large quadrilateral figure is a 20 series of concentric circles C, equidistant from each other and arranged as shown in the drawing, the sides of the largest figure A being disposed tangentially to the largest circle, so that said circle touches the sides of the 25 figure A at four equidistant points. The inner or smallest circle is contained within the central quadrilateral figure and touches the four sides of said small quadrilateral figure at four equidistant points. The remain-

ing concentric circles are inscribed in their 30 proper quadrilateral figures, the sides of which are disposed tangentially to their respective circles. Through each of the opposite angles of the large quadrilateral figure diagonal lines D are drawn, which diagonal 35 lines bisect each other in the center of the smallest of the five circles. Similarly all the smaller quadrilateral figures, with the exception of the four whose inner sides are in contact with the smallest circle and whose outer 40 sides are in contact with the next larger circle, have diagonal lines E intersecting each other at right angles, as shown in the drawing. These four quadrilateral figures or squares referred to have but one diagonal line 45 each, extending in the direction as shown.

Having thus described the invention, what I claim as new, and desire to secure by Letters Patent, is—

The design for a game-board, as herein 50 shown and described.

In testimony whereof I have signed my name to this specification in the presence of two witnesses.

HENRY BOGGIS.
